PHOTOGRAPHIC FLASH LIGHT

Lester A. Dine and Edgar S. Lemmey, Levittown, N. Y.

Application May 7, 1958, Serial No. 50,793

Term of patent 14 years

(Cl. D61—1)

Figure 1 is a perspective view of a photographic flash light, showing our new design;

Figure 2 is a front elevational view;

Figure 3 is a side elevational view, the opposite side being substantially a mirror image thereof; and

Figure 4 is a rear elevational view thereof.

The attachment cord and plug has been broken away in Figures 2, 3 and 4 for convenience in illustration.

Portions of the drawing figures have been diagonally lined to indicate transparency.

The dominant features of our new design are shown in solid lines in the drawing.

We claim:

The ornamental design for a photographic flash light, as shown and described.
